UNITED STATES PATENT OFFICE.

GEORGE WALDEMAR BUNGAY, OF BROOKLYN, NEW YORK, ASSIGNOR TO ACME DIE-CASTING CORPORATION, A CORPORATION OF NEW YORK.

DIE-CASTING MACHINE.

1,279,650.

Specification of Letters Patent. Patented Sept. 24, 1918.

Application filed April 20, 1917. Serial No. 163,406.

To all whom it may concern:

Be it known that I, GEORGE WALDEMAR BUNGAY, a citizen of the United States, residing at the borough of Brooklyn, in the county of Kings and State of New York, have invented certain new and useful Improvements in Die-Casting Machines, of which the following is a specification, reference being had therein to the accompanying drawings forming part thereof.

My invention relates to die-casting machines and has for its general object the production of a machine which will successfully cast aluminum and other similar metals which heretofore have given trouble in forming into castings under pressure, known as die-castings. A serious source of trouble in casting aluminum and the like by means of die-casting machines as heretofore commonly constructed has been the location in the molten metal of various working parts, such as pistons and valves, and therefore a more particular object of my present invention is to construct an effective die-casting machine which has no piston, valve or the like located in the molten metal. Other objects and advantages of my invention will hereinafter appear.

My present invention includes a movable pressure chamber or casting pot provided with a duct terminating in a nozzle adapted to be submerged below the surface of the material to be cast so as to permit such material to flow into the pressure chamber through the nozzle, this nozzle providing the only inlet by which such material may enter the pressure chamber, means being provided for then raising the nozzle to casting position above the surface of the material, and means for admitting suitable pressure fluid, such as compressed air, into the pressure chamber for forcing out the material through the nozzle and into a die or mold. My invention also includes various features of construction and combinations of parts as will appear from the following description.

I shall now describe the die-casting machine embodying my invention illustrated in the accompanying drawings and shall thereafter point out my invention in claims.

Figure 1 is a side elevation of the com-

plete machine as it appears at rest in the idle condition, parts being broken away to show the submerged position of the nozzle 55 of the dipper or pressure chamber.

Fig. 2 is a vertical longitudinal central section of the complete machine with parts thereof shown in the casting position.

Fig. 3 is a partial vertical transverse section on a plane indicated by the line 3—3 of Fig. 2 as viewed from the left and shows the latching device for locking the dipper or pressure chamber at the casting position.

Fig. 4 is a plan of the complete machine 65 as it appears in Fig. 2.

Fig. 5 is an enlarged horizontal section taken on the line 5—5 of Figs. 1 and 6 as viewed from above and illustrates the valve device in control of the supply of compressed air for the pressure chamber or dipper.

Fig. 6 is a vertical section longitudinally of the machine on a plane indicated by the line 6—6 of Figs. 4 and 5 as viewed from below and of Fig. 7 as viewed from the left.

Fig. 7 is a vertical section transversely of the machine on a plane indicated by the line 7—7 of Figs. 1 and 6 as viewed from the right.

Fig. 8 is a perspective view of the operating means, appearing in Figs. 1 and 4, for the air-controlling valve device illustrated in Figs. 5, 6 and 7.

Fig. 9 is an enlarged horizontal section 85 on a plane indicated by the line 9—9 of Figs. 1 and 10 as viewed from above and shows the valve device which is in control of the steam or other operating fluid employed to raise and lower the nozzle of the 90 dipper or pressure chamber and to close and open the die.

Fig. 10 is a partial vertical section longitudinally of the machine on a plane indicated by the line 10—10 of Figs. 4 and 9 as 95 viewed from below.

Fig. 11 is a partial horizontal section similar to Fig. 9 on a plane indicated by the line 11—11 of Figs. 1 and 10.

Excepting as to the features involving the present invention, the die-casting machine illustrated in the accompanying drawings is generally of a construction similar to that forming the subject of my application for

patent for casting apparatus filed October 5, 1915, Serial No. 54,123. Also the controlling means appearing in Figs. 1 and 4 and more particularly illustrated in Figs. 9, 10 and 11 of the accompanying drawings is of substantially the same construction as that forming the subject of my application for patent for control boxes filed August 30, 1916, Serial No. 117,596. The two above noted applications 10 contain claims, respectively, for the general construction of the machine illustrated in the accompanying drawings and for the controlling means employed and also illustrated in the accompanying drawings.

15 The die-casting machine illustrated in the accompanying drawings as an embodiment of my invention has a usual furnace or fire box 1 in the upper part of which is located a receptacle for the material to be cast or 20 melting pot 2 of substantially usual construction and arrangement. A curved casting pot or pressure chamber 3, which is shown as resembling the shape of the capital letter J, dips into the molten metal contained in the melting pot 2. The pressure chamber 3 is provided with an upwardly curved duct 4 which terminates in an upwardly directed nozzle 5 which in the inactive or non-operative condition of the machine illustrated in Fig. 1 is submerged below 30 the surface of the molten metal in the melting pot 2, but which in the casting position in the operation of the machine as illustrated in Fig. 2 is located above the surface of the molten metal and is shown as raised just 35 above the edge of the melting pot 2. The main part or body of the pressure chamber 3 at the end thereof opposite to the nozzle 5, rises above the top of the melting pot 2 and is shown in the drawings as of gradually 40 increasing cross-section in its upper part.

45 The pressure chamber 3 is supported by a cross-piece 6 which may be formed integral with the pressure chamber 3 and which at its opposite ends is provided with trunnions 7 pivoted in bearings 8 which are supported upon the top of the furnace or fire box 1. The pivoted trunnions 7 provide for rocking the pressure chamber 3 back and forth between the submerged position of the nozzle 5 appearing in Fig. 1 and the exposed or casting position of the nozzle 5 appearing in Fig. 2. In the lowered position of the nozzle 5, appearing in Fig. 1, the molten 50 metal contained in the melting pot 2 will flow into the pressure chamber 3 through the submerged open nozzle 5 and duct 4, and in the position of the nozzle 5, appearing in Fig. 2, molten metal contained in the pressure chamber 3 may be ejected or discharged 55 therefrom through the delivery duct 4 and nozzle 5 into a suitable die. It will be noted that the nozzle 5 of the pressure chamber 3 is raised only slightly above the surface of the 60 molten metal in the casting operation, so that

the nozzle 5 will at all times be substantially of the same temperature as the molten metal in the melting pot 2. It will also be noted that the pressure chamber 3 acts as an automatic dipper for dipping up charges of the molten metal from the melting pot 2 through the same opening in the nozzle 5 through which these charges are afterward delivered or ejected into the die, there being no separate inlet opening and consequently no troublesome valve working in the molten metal. The upper or outer end of the body of the pressure chamber 3 is closed by means of a head 9 and the head 9 is shown as having therein a port 10 to which is connected a pipe 11 for supplying suitable pressure fluid, such as compressed air, to the upper end of the pressure chamber 3 for forcing the molten metal from the pressure chamber 3 through the delivery duct 4 and out of the nozzle 5 into the die. It will be noted that the pressure chamber 3 has therein only two openings, one of these being the nozzle opening for the ingress and egress of the molten metal, and the other being the opening 10 for the admission and exhaust of compressed air to act upon the molten metal contained in the pressure chamber 3. The means for operating the die and for controlling the compressed air will be hereinafter described. 95

Fluid pressure means are provided for rocking the pressure chamber 3 between its two positions, and such operating means for the pressure chamber 3 will now be described. The upper part of the body of the pressure chamber 3 above the top of the melting pot 2 is provided with a rearwardly extending operating arm 12 shown as formed integral with the pressure chamber 3. The operating arm 12 of the pressure chamber 3 is connected to the upper end of a vertical piston rod 13 which carries at its lower end and is operated by a double-acting piston 14 in a cylinder 15 located at the rear of the fire box 1. The cylinder 15 is shown as having a separable upper end or head 16 from which this cylinder is supported by means of a bracket arm 17 extending from the head 16 and secured to the top plate of the fire box 1, as clearly appears in the drawings. Steam is admitted to or exhausted from the upper and lower ends of the cylinder 15 through upper and lower steam pipes 18 and 19. The means for controlling the steam supply for the operating cylinder 15 will be described hereinafter. It is only necessary to note now that when steam is supplied to the cylinder 15 through the upper steam pipe 18 and exhausted through the lower steam pipe 19, the pressure chamber 3 will be rocked from the filling position thereof appearing in Fig. 1 to the casting position appearing in Fig. 2; and when steam is supplied to the cylinder 15

through the lower steam pipe 19 and exhausted through the upper steam pipe 18, the pressure chamber or dipper 3 will be returned from the casting position shown 5 in Fig. 2 to the inactive or filling position, illustrated in Fig. 1.

Locking means are provided for rigidly holding the pressure chamber 3 at the casting position shown in Fig. 2 so that it will 10 be able unyieldingly to resist the downward pressure of the die upon the nozzle 5 in the casting operation. This locking device for the pressure chamber 3 comprises a latch hook 20 pivoted upon a stud 21 carried by 15 the cylinder-supporting bracket 17 at the rear of the fire box 1 and shown as projecting from its supporting stud 21 diagonally upward into the path of the operating arm 12 as this arm descends. The latch hook 20 20 is pressed toward the engaging position by the weight of a projecting bent lever 22 which is employed for manually disengaging the latch hook 20 from the operating arm 12 when this arm is to be raised for 25 depressing the nozzle 5. As the nozzle 5 is raised from the submerged filling position shown in Fig. 1 to the casting position appearing in Fig. 2, the latch hook 20 is in the path of the descending operating arm 12 30 and the arrangement is such, as will be clear from the drawings, particularly Fig. 3, that the downwardly moving arm 12 will push aside the hooked end of the latch hook 20 and will be automatically engaged therewith 35 when the operating arm 12 has reached its limit of downward movement for raising the nozzle 5 to the casting position, as is clearly illustrated in Figs. 2, 3 and 4 of the drawings. It will now be clear that the 40 nozzle 5 of the pressure chamber 3 will thus be positively locked against downward movement without any reliance upon the pressure of steam within the operating cylinder 15. When the casting operation is 45 completed the latch hook 20 is released or disengaged by an attendant standing at the back of the machine, who is commonly employed anyway for performing other duties, such as wiping off the die and taking away 50 the finished castings. When the pressure chamber 3 has been, as above described, locked in the casting position, it becomes for the time being and during the casting operation a stationary metal-containing chamber, 55 the nozzle 5 of which is just above the surface of the molten metal contained in the melting pot 2. After the pressure chamber 3 has been thus brought to the casting position, the die is next brought to the casting 60 position and clamped upon the nozzle 5, and the parts of the machine for doing this resemble in a general way corresponding parts of the machine forming the subject of my hereinbefore mentioned application for patent for casting apparatus, Serial No.

54,123, filed October 5, 1915, and will now be described.

The die is shown as comprising two relatively movable members 23 and 24 each of which has a recess 25 in its lower edge so 70 located that when the die members 23 and 24 are together in the position for casting the recess 25 fits over the nozzle 5. An inlet port 26, shown as formed by a groove in the surface of each tie member, leads from the recess 25 to the inside of the die. The inlet port 26 registers with the opening formed by the nozzle 5 for the admission of the molten metal directly from the nozzle 5 into the die. Also it is to be noted that the nozzle 5 of the pressure chamber 3 rises from complete submergence to the position for casting which is only just above the surface of the molten metal in the melting pot 2, so that the nozzle 5 and the metal therein are 80 at all times kept hot so that the molten metal will freely flow.

The means for supporting the die members 23 and 24 and for moving them relatively to each other and to the nozzle 5 will 90 now be described. A frame 27 is shown as formed integral with the top plate of the fire box 1, and extending from this frame are two horizontal parallel rods 28, one at each side of the machine, the outer ends of these 95 rods 28 being shown as provided with a support 29. On each of the rods 28 and adjustable longitudinally thereof is a split bearing 30 which may be firmly clamped in place by means of a clamp bolt 31 (see Fig. 1). To 100 facilitate the adjustment of the bearing block 30, gear teeth forming racks 32 are provided along the lower side of the rods 28, and these racks 32 are engaged by pinions 33 carried by a transverse shaft 34 which 105 is journaled in the bearing blocks 30 and provided at one end with a crank 36. As will presently appear, the adjustable bearing blocks 30 provide for adjusting the die support so that dies of various sizes may be 110 brought into proper casting relation with the nozzle 5.

An operating cylinder 37 for the die is provided on its lower side with a projecting supporting lug 38 which is located between the bearing blocks 30 and is pivoted to them by means of a trunnion shaft 39 about which the operating cylinder 37 together with the parts carried thereby may rock as a pivot. The die-operating cylinder 37 is arranged 115 longitudinally of the machine and at its end nearest to the melting pot 2 and nozzle 5 has a head 40 from which rigidly project four rectangularly arranged parallel rods 41 which extend back over the melting pot 2. The outer or projecting ends of the rods 41 120 support a die head 42 which may be adjusted along the rods 41 by means of nuts 43. The die member 23 is secured to and supported by this die head 42. The nuts 43 provide for 125 130

the independent adjustment of the die head 42 together with the die member 23 carried thereby.

A second die head or die carrier 44 for the other die member 24 is slidably mounted, by means of bearing sleeves 45, upon the longitudinal guide rods 41. The die carrier 44 carries two vertically arranged spaced projecting plates 46 which support the die member 24. The slidable die head or die carrier 44, together with the guide rods 41 and die head 42, is supported by means of two vertically arranged side bars 47 which pass through bearings in and are guided by the bearing sleeves 45 of the die carrier 44. The upper ends of the vertical supporting bars 47 are connected together by a cross-bar 48 which, at a middle point thereof, adjustably supports the die carrier 44 by means of a depending adjusting screw 49 which provides for the vertical adjustment of the die heads 42 and 44 relatively to the nozzle 5, so as to accommodate dies of various sizes. The lower ends of the vertical supporting bars 47 are connected by a cross shaft 51 which is provided with a flanged roller 52 adjacent to each of the bars 47. The rollers 52 are adapted to travel in guideways formed by means of slots 53 in the frame 27, these roller-guiding slots 53 being shown as extending longitudinally and as slightly inclined downward toward the fire box 1, as clearly appears in the drawings. The rollers 52 and inclined guideways 53 perform the important function of clamping the die members 23 and 24 firmly upon the slightly projecting nozzle 5 in the hereinbefore described locked casting position of the latter, as appears in Figs. 2 and 4 of the drawings, this clamping function being performed when the die carrier 44 is operated to slide along the guide rods 41 and to move the die members 24 up to the die member 23. A second function of the rollers 52 and guideway 53 is to raise the die members 23 and 24 away from the nozzle 5 and above the melting pot 2 when the die members 23 and 24 are moved apart by the sliding of the die carrier 44 in the opposite direction upon the guide rods 41, as appears in Fig. 1 of the drawings. These two functions of the rollers 52 and guideways 53 will presently more clearly appear in connection with the description of the means for operating the die, which will now be given.

The die carrier 44 is operated in its sliding movement on the guide rods 41 by means of a piston rod 54 connected thereto and to a double-acting piston 55 in the die-operating cylinder 37. Steam for operating the piston 55 and the parts connected thereto is admitted to the cylinder 37 through steam pipes 56 and 57 connected to opposite ends of the cylinder 37 and is exhausted through the same pipes. It will now be evident that

when steam is admitted to the cylinder 37 through the pipe 56 at the right end thereof, as the machine is illustrated in the drawings, the die member 24 carried by the slidable die head or die carrier 44 will be moved up toward and against the die member 23 carried by the other die head 42, and at the same time the rollers 52 traveling down the inclined guideways 53 will bring these closed-together die members 23 and 24 down upon the firmly positioned locked nozzle 5 and will securely clamp the die to the nozzle 5, the rollers 52 in this clamping action bearing upon the upper surfaces of the guideways 53. When steam is admitted to the cylinder 37 by the pipe 57 at the left end of the cylinder 37, as the machine is shown in the drawings, the die carrier 44 together with the die member 24 carried thereby will be retracted, causing the rollers 52 to travel up the inclined guideways 53, thereby first to unclamp the die from the nozzle 5 and then to raise the die members 23 and 24 away from the nozzle 5 and to a point above the melting pot 2, as appears in Fig. 1, this raising of the die members 23 and 24 taking place as these members are separated by the sliding of the die carrier 44 toward the die-operating cylinder 37, as will be readily understood. In view of the fact that the molten metal is fed to the die under pressure, it is very important both that the nozzle 5 of the pressure chamber 3 shall be firmly locked in place and that the die shall be securely clamped to the nozzle 5.

The die-casting machine illustrated in the drawings is so arranged that the pressure chamber 3 is first rocked to raise the nozzle 5 and lock it at its raised casting position, where it is held while the die members 23 and 24 are operated to close together and be clamped upon the nozzle 5. Next the molten metal is forced from the pressure chamber 3 through the duct 4 and nozzle 5 into the die. After this the die members 23 and 24 are unclamped, separated and elevated to release the casting, and finally the pressure chamber 3, after it has been unlocked, is rocked to again submerge the nozzle 5.

The casting, which is carried by the die member 24, is ejected therefrom by means of ejector pins 58 shown as projecting from a plate 59 carried by ejector rods 60 passing through and guided by the die carrier 44. Upon the movement of the die carrier 44 toward the operating cylinder 37 the free ends of the ejector rods 60 come in contact with abutment projection 61, carried by an abutment plate 62 shown as adjustably mounted upon the guide rods 41 by means of nuts 63, and cause the ejector pins 58 to push the casting from the die member 24.

Any suitable valve-controlling means may be employed for operating the pistons 14 and 55 of the respective fluid pressure cylin-

ders 15 and 37, for successively operating the pressure chamber 3 and the die carriers 42 and 44 in proper succession; as above noted, so that, starting from the non-operative position of rest of the machine appearing in Fig. 1, the nozzle 5 of the pressure chamber 3 will be first elevated while the die carriers 42 and 44 are maintained in the elevated and separated condition; and so that these die carriers will be closed together and moved downward into clamping relation with the nozzle 5 during the time that this nozzle is maintained at the elevated position, as above noted; and so that then, after the molten metal has been forced into the die, the die members 23 and 24 will be unclamped and raised and separated; and so that, as a final part of the operation after the making of a casting, the pressure chamber 3 will be rocked to depress and again submerge the nozzle 5. In the machine illustrated in the drawings, I have employed for this purpose the fluid pressure controlling means which forms the subject of my hereinbefore mentioned application for patent for control boxes filed August 30, 1916, Serial No. 117,596, and such means will be herein described to an extent necessary to make clear the operation of the machine of the present invention.

Secured to the head 40 of the die-operating cylinder 37 is a two-part casing comprising a cam chamber 64 and a valve chamber 65, which contain the valves and the operating mechanism therefor, as is more particularly illustrated in Figs. 9, 10 and 11 of the drawings. The valve chamber 65 is shown as of substantially rectangular shape, and one corner of this chamber, shown as the upper right hand corner in Fig. 9, is partitioned off to form an inlet header or inlet manifold 66 which extends throughout the full length vertically of the valve chamber 65 and to the upper end of which there is connected a steam supply pipe or inlet pipe 67 (see Figs. 1, 4, 9 and 10). In the opposite corner of the valve chamber 65 diagonally from the steam inlet manifold 66 there is similarly partitioned off an exhaust manifold or exhaust header 68 which also extends vertically throughout the length of the valve chamber 65 and which at the top and front thereof is provided with an exhaust pipe 69 (see Figs. 1, 4, 9 and 10). The remaining irregular space within the valve chamber 65 is divided by three transverse partitions so as to form a tier of four small chambers or pockets 70, 71, 72 and 73 arranged vertically one above the other alongside of and between the inlet manifold 66 and the exhaust manifold 68, as most clearly appears in Fig. 10, these individual pockets being shown as numbered from the top downward. Four spring-pressed inlet valves 74, 75, 76 and 77, ar-

ranged in a vertical series and shown as of the puppet type, are adapted to connect the inlet manifold 66 with the respective individual steam pockets 70, 71, 72 and 73, and a similar series of exhaust valves 78, 79, 80 and 81 are in control of communication between these respective steam pockets and the exhaust manifold 68. Connected to the respective individual steam pockets 70, 71, 72 and 73 are the respective pipes 75 57, 56, 19 and 18, of which, as hereinbefore described, the pipe 57 is connected to the die-operating cylinder 37 at the left end thereof, the pipe 56 is connected to this cylinder at the right thereof, the pipe 19 is 80 connected to the lower end of the pressure-chamber-operating or nozzle-operating cylinder 15, and the pipe 18 is connected to the upper end of the same cylinder. It will now be evident that any one of these 85 steam pipes may be connected either with the steam inlet manifold 66 or with the exhaust manifold 68 through its individual steam pocket provided with an inlet valve and an exhaust valve as above described. 90

A cam mechanism now to be described is provided for operating these valves in the proper sequence or succession. A vertical cam shaft 82 is journaled in the cam chamber 64 and at its upper end is exteriorly 95 provided with an operating wheel 83 from which there projects an operating handle 84 (see Figs. 1 and 4). The inlet valve and the exhaust valve for each of the individual steam pockets 70, 71, 72 or 73 are operated 100 to be opened alternately by means of the cams carried by the cam shaft 82 and acting upon rock arms which engage the stems of the respective valves. For example, the steam inlet valve 74 for the pipe 57 which 105 is connected to the left end of the cylinder 37 is operated by a cam 85 which acts upon a rock arm 86, as shown in Fig. 9, and the exhaust valve 78 for this same steam pipe 57 is operated by a cam 87 arranged along- 110 side of the cam 85 and acting upon an oppositely arranged rock arm 88. Each other pair of valves, comprising an inlet valve and an exhaust valve for the respective pipes 56, 19 and 18, is similarly controlled 115 by a pair of cams acting upon a similar pair of rock arms. For example, there is shown in Fig. 11 a cam 89 which acts upon a rock arm 90 to operate the inlet valve 77 for the pipe 18 which admits steam to the 120 upper end of the nozzle-operating cylinder 15 for raising the submerged nozzle 5 to the casting position, and there is also shown another cam 91 alongside of the cam 89 on the cam shaft 82 and this cam 91 acts upon 125 an oppositely arranged rock arm 92 for operating the exhaust valve 81 for this same pipe 18.

It is to be noted that the raised cam faces of the different cams are longer or shorter 130

according to the length of time that the respective valves are required to be held open during the rotative valve-controlling movement of the cam shaft 82. The valve-controlling device illustrated in the drawings is constructed and arranged so that a complete operation of the die-casting machine is caused to take place during two half rotations of the cam shaft 82 which, so far as 5 the operation of the machine is concerned, may be in the same direction of rotation, thereby to make one complete rotation of this shaft, or the half rotations may be in opposite directions, half way around and half way back again, and this is the manner 10 in which the machine illustrated in the drawings has been operated, the half rotations of the cam shaft 82 being manually imparted by means of the operating handle 84, which 15 is moved from the position appearing in Fig. 1 half way around to the position shown in Fig. 4 and back again, by an operator standing at the front of the machine. In view 20 of the fact that the valve-operating cams are made in symmetrical halves, the operating handle 84 may be moved in either direction, around toward the front or around toward the back, from the position appearing in 25 Fig. 1, but it has been found most convenient 30 in the operation of the machine to move this handle through the front half of the circle, and the valve-operating action of the cams will now be described in reference to such movement of the handle 84.

35 It will be noted that the cam 85 for operating the inlet valve 74 of the pipe 57 has an extended raised concentric cam face and that the companion cam 87 for operating the corresponding exhaust valve 78 has a short or 40 peaked raised cam face. In this connection it is to be understood that the pair of cams (not appearing in the drawings) for operating the inlet and exhaust valves 75 and 79 respectively for the pipe 56 leading to the 45 other end of the operating cylinder 37, are complementary to the cams 85 and 87 in that the cam for operating the inlet valve 75 will have a short or peaked raised cam face, while the cam for operating the exhaust 50 valve 79 will have a concentric extended cam face similar in this respect to the cam 85 for the inlet valve 74. Likewise it is to be understood that the pair of cams (not appearing in the drawings) for controlling the 55 valves of the pipe 19 will be similarly complementary to the cams 89 and 91 in control of the valves for the pipe 18. In this connection it is to be noted that the cam 89 for operating the inlet valve 77 for the pipe 18 60 leading to the upper end of the pressure-chamber-operating cylinder 15, has an extended raised cam surface for holding open this valve during the casting operation, while the cam 91 has a short or peaked raised

cam surface, for opening the exhaust valve 65 81 for the upper end of the cylinder 15 at the position of rest of the machine appearing in Fig. 1. Therefore, in the above noted complementary pair of cams (not shown) the cam for operating the inlet valve 76 of the pipe 19 leading to the lower end of the cylinder 15, will have a correspondingly short or peaked raised operating face, while its companion cam for operating the exhaust valve 80 for the pipe 19 will have an 70 75 extended raised cam face.

When the operating handle 84 is rotated through a quarter turn or ninety degrees it will be noted that no change takes place in the position of the valves in control of the 80 steam pipes 56 and 57 of the cylinder 37 and that therefore the open and elevated position of the die members 23 and 24 appearing in Fig. 1 will be maintained without change during this movement. However, as will be 85 clear from an inspection of Fig. 11, during this quarter turn of the cam shaft 82, a complete change has been effected in the positions of the valves controlling the nozzle-operating cylinder 15; the exhaust valve 81 90 of the pipe 18 having been first closed by the peaked or short-faced cam 91 followed immediately by the opening of the inlet valve 77 of this pipe by the long or extended-faced cam 89. The complementary cams not shown 95 have effected the reverse result as to the position of the valves for the pipe 19 leading to the other or lower end of the cylinder 15 and have closed the inlet valve 76 and opened the companion exhaust valve 80. It will now 100 be clearly evident that the piston 14 in the cylinder 15 will be actuated and forced to the bottom of the cylinder 15, thereby to rock the pressure chamber 3 and raise its submerged nozzle 5 in the manner herein-before described.

As the operating handle 84 is moved through the remaining ninety degrees to the position thereof appearing in Fig. 4, to complete the half rotation of the cam shaft 82, 110 the position of the valves for the cylinder 15 which actuates the pressure chamber 3 will not be changed, but the position of the valves for the die-operating cylinder 37 will be completely changed, as will be clear from an inspection of Figs. 9 and 11, it being noted that the extended concentric raised cam face of the cam 89 will maintain the inlet valve 77 open while the corresponding exhaust valve 81 will be kept closed by its operating 115 cam 91, and that now the cam 85 has closed the inlet valve 74 of the pipe 57 of the operating cylinder 37 and the companion cam 87 having the short cam projection has opened the corresponding exhaust valve 78, while the complementary cams not shown have at the same time closed the exhaust valve 79 and opened the intake valve 75 of the pipe 56.

leading to the other end of the cylinder 37. The piston 55 of the cylinder 37 will now be actuated to close together the die members 23 and 24 and to lower and clamp them upon the rigidly locked nozzle 5, as hereinbefore described. All parts of the machine have now moved from the open position of rest appearing in Fig. 1 to the casting position appearing in Figs. 2 and 4 of the drawings.

10 In this position of the parts of the machine, compressed air is admitted into the body part of the pressure chamber 3 through the port 10 and pipe 11, and forces the molten metal from the pressure chamber 3 out through the duct 4 and nozzle 5 and through the port 26 into the die or mold comprising the sections or members 23 and 24.

15

When the casting has set the operating handle 84 is reversed and brought back from the position appearing in Fig. 4 to the original position appearing in Fig. 1; or, as hereinbefore noted, instead of reversing the movement of the handle 84 its movement could be continued in the same direction to complete the rotation and with the same result. With the return of the operating handle 84 to its original position, as shown in Fig. 1, all of the valves are again actuated but in the reverse order, as will be readily understood, so that first the die members 23 and 24 will be unclamped and raised from the nozzle 5 and thereafter the pressure chamber 3, which in the meantime has been unlocked by the attendant, will be rocked away from the casting position to the position of submersion of the nozzle 5, so that when the operating handle 84 is at its original position appearing in Fig. 1, the operating parts of the machine will then have successively changed in the order recited from their position appearing in Fig. 2 to the position thereof shown in Fig. 1, ready for the next casting operation.

The means for controlling the pressure fluid which is supplied through the pipe 11 to the pressure chamber 3 for ejecting the molten metal therefrom into the closed die will now be described. A valve casing 93 is supported by a plate 94 secured to the side of the fire box 1, as appears in Fig. 1. The valve casing 93 has therein a middle chamber 95 to which the pipe 11 leading to the pressure chamber 3 is connected. Above this middle chamber 95 the casing 93 is provided with an inlet chamber 96 to which is connected a supply pipe 97 which may proceed from a source of supply of any suitable pressure fluid, such as compressed air. Below the middle chamber 95 the valve casing 93 is provided with an exhaust chamber 98 which opens to the atmosphere through an exhaust port 99. An inlet valve 100 of the puppet type, closed by a spring 101, controls communication between the inlet chamber

96 and the middle chamber or distributing 65 chamber 95, and an exhaust valve 102 of the puppet type, closed by a spring 103, controls communication between the middle chamber 95 and the exhaust chamber 98. The stems of the valves 100 and 102 project below the 70 valve casing 93, and for opening these valves are adapted to be engaged by the respective arms of a two-arm rock lever 104 carried by a longitudinally extending rock shaft 105 which is journaled in bearings on the supporting plate 94, as appears most clearly in Fig. 1. The arrangement is such, as will be evident from an inspection of the drawings, particularly Fig. 7, that one of these valves 100 or 102 will not be opened by the rocker 75 80 85 90 95 100 105 110 115 120 125 104 until the other valve has been permitted to close. Normally the inlet valve 100 is maintained in closed condition and the exhaust valve 102 is maintained open, so that there will be no fluid pressure upon the molten metal contained in the pressure chamber 3, such pressure being only applied thereto when it is desired to force such metal from the pressure chamber 3 into the closed die. This condition of the valves 100 and 102 is maintained by means of a retractile spring 106 connected to a lever 107 on the rock shaft 105 and anchored at its other end to a stationary part of the machine, the spring 106 being strong enough to overcome the valve-closing spring 103 and thereby to hold the exhaust valve 102 open. The valves 100 and 102 are operated to close the exhaust valve 102 and to open the inlet valve 100 for admitting compressed air, or other suitable pressure fluid, into the pressure chamber 3 by means of a manually operated handle lever 108 which extends upward from the rock shaft 105 and which is shown as forming a continuation from the outer end of the rock shaft 105. To admit the pressure fluid to the pressure chamber 3 for forcing the molten metal therefrom into the die, the hand lever 108 is moved in a counter-clockwise direction or to the left as viewed from the right in Fig. 1, thereby to open the inlet valve 100 while the exhaust valve 102 remains closed, as appears in Fig. 7. After the molten metal has been forced into the die, the pressure in the pressure chamber 3 is released before the unclamping of the die members 23 and 24 from the nozzle 5. To release the pressure of pressure fluid in the pressure chamber 3, it is only necessary to let go of the handle lever 108 whereupon the retractile spring 106 will move this lever to the right, rotating the rock shaft 105 in a clockwise direction as viewed from the right in Fig. 1, thereby oscillating the rocker 104 to permit the inlet valve 100 to close and also so as to open the exhaust valve 102 for the escape of the pressure fluid from the pressure chamber 3 through the pipe 11.

to the atmosphere through the exhaust chamber 98 and port 99.

Safety means are provided to prevent the admission of pressure fluid to the pressure chamber 3, excepting when the die members 23 and 24 are securely clamped to the nozzle 5. This safety device comprises a U-shaped guard 109 which is carried by and is adjustable longitudinally in a supporting bracket 110 shown as secured to the lowermost adjacent bearing sleeve 45 of the die carrier 44, so that this U-shaped guard 109 partakes of the movement of the movable die carrier 44. The guard 109 for the hand lever 108 is arranged so that when the die carrier 44 moves away from its operating cylinder 37 to close together the die members 23 and 24 and clamp them upon the nozzle 5, the hand lever 108 may then freely pass the reversely projecting free end of this guard member, as is shown in Figs. 4 and 8 of the drawings. However, in the retracted position of the die carrier 44, in which the die members 23 and 24 are separated and elevated above the nozzle 5, the hand lever 108 is engaged by the reversely projecting guard member 109, thereby locking the lever 108 so that it cannot be moved to admit pressure fluid to the pressure chamber 3, this locked position of the hand lever 108 being illustrated in the drawings in Fig. 1. This locking arrangement prevents the possibility of operating the hand lever 108 at the wrong time and thereby ejecting molten metal from the pressure chamber 3 through its duct 4 and nozzle 5 at a time when the die members 23 and 24 are not securely clamped to the nozzle 5, the guard 109 being so adjusted that it will only release the hand lever 108 in the casting position of the parts of the machine.

The complete operation of the machine can now be readily understood and will be briefly noted. Starting from the position of rest of the machine illustrated in Fig. 1, the operating handle 84 of the wheel 83 of the valve-operating cam shaft 82 is first moved through an arc of one hundred and eighty degrees, to the position shown in Fig. 4, thereby to cause the successive lifting and automatic locking in position of the nozzle 5 and the subsequent closing together and clamping to this nozzle of the die members 23 and 24, as above described, this being the casting position of these parts of the machine illustrated in Figs. 2 and 4. The hand lever 108, which has been unlocked by the movement of the die carrier 44, may now be moved to rock the rock shaft 105 for thereby admitting pressure fluid, such as compressed air, to the top of the pressure chamber 3, above the surface of the molten metal contained therein, thereby forcing the molten metal from the pressure chamber 3 through its duct 4 and nozzle 5 into the mold or die

formed by the closed-together and clamped die members 23 and 24. After a brief period of rest, for the sufficient hardening or setting of the casting, the hand lever 108 is simply released, upon which it is automatically returned by the retractile spring 106, which, as above noted, is strong enough to overcome the valve spring 103, with the result that first the supply of pressure fluid to the pressure chamber 3 is cut off by the closing of the inlet valve 100 and immediately thereafter the pressure fluid contained in the pressure chamber 3 is permitted to escape or is exhausted to the atmosphere by the opening of the exhaust valve 102. After this brief interval of cooling of the casting and the subsequent release of the fluid-pressure-controlling hand lever 108, the operating handle 84 of the wheel 83 is brought back through a half rotation from the position illustrated in Fig. 4 to its original position, shown in Fig. 1, thereby, as above described, successively to raise and separate the die members 23 and 24 and to lower and again submerge the nozzle 5 of the tipping or rocking pressure chamber 3 which, in the meantime, has been unlocked by the attendant standing at the back of the machine raising up the bent lever 22 of the latch hook 20. The machine is now ready for successive repetitions of this complete operation.

In this connection it should be noted that in making small castings the pressure chamber 3 will be found to contain enough molten metal to make several of these castings successively without the necessity of moving or rocking this pressure chamber to dip up more molten metal from the melting pot 2 through the nozzle 5, and in such cases the pressure chamber 3 may be left locked in the casting position during several successive casting operations. This result is accomplished by returning the operating handle 84 from the casting position, appearing in Fig. 4, through only ninety degrees of its return movement, thereby to unclamp and elevate and separate the die members 23 and 24 without the rocking of the pressure chamber 3, which is maintained and kept locked at the casting position. From this half-way returned or ninety degree position of the operating handle 84, this handle is not brought all the way back to its original position, but is reversed and returned to the casting position through the last ninety degrees of its one hundred and eighty degree arc of complete movement. This will result in the die members 23 and 24 being again closed together and clamped upon the nozzle 5, for a second casting operation without the nozzle 5 having been submerged between the casting operations. Such casting operations without the dipping or submerging of the nozzle 5 may be successively performed so

long as there is sufficient metal contained in the pressure chamber 3, it being understood, of course, that the hand lever 108, which is unlocked by the closing together and the 5 clamping of the die members 23 and 24, is rocked once for each casting operation.

It is obvious that various modifications may be made in the construction shown in the drawings and above particularly described within the principle and scope of 10 my invention.

I claim:

1. A casting machine having, in combination, a receptacle for the material to be cast, a movable die, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, means for raising said nozzle above the surface of such material, and means for supplying and admitting a fluid under pressure into the pressure chamber to act upon the material within the pressure chamber and eject such material from the pressure chamber through said nozzle directly into the die.

2. A casting machine having, in combination, a receptacle for the material to be cast, a movable die, a pressure chamber pivoted for rocking movement and provided with a duct terminating in a nozzle adapted to be submerged below the surface of such material for permitting such material to flow into the pressure chamber through said nozzle, said nozzle providing the only inlet for such material to enter the pressure chamber, fluid pressure means for imparting rocking movement to the pressure chamber for raising the nozzle above the surface of such material, and means for supplying and admitting a fluid under pressure into the pressure chamber to act upon the material within the pressure chamber and eject such material from the pressure chamber through the nozzle directly into the die.

3. A casting machine having, in combination, a receptacle for the material to be cast, a movable die, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, means for raising said nozzle above the surface of such material, means for locking the pressure chamber in the casting position with its nozzle above the surface of the material in the receptacle, and means for supplying and admitting a fluid under pres-

sure into the pressure chamber to act upon 65 the material within the pressure chamber and eject such material from the pressure chamber through said nozzle directly into the die.

4. A casting machine having, in combination, a receptacle for the material to be cast, a movable die, a pressure chamber pivoted for rocking movement and provided with a duct terminating in a nozzle adapted to be submerged below the surface of such material for permitting such material to flow into the pressure chamber through said nozzle, said nozzle providing the only inlet for such material to enter the pressure chamber, fluid pressure means for imparting rocking 80 movement to the pressure chamber for raising the nozzle above the surface of such material, means for locking the pressure chamber in the casting position with its nozzle above the surface of the material in the receptacle, and means for supplying and admitting a fluid under pressure into the pressure chamber to act upon the material within the pressure chamber and eject such material from the pressure chamber through 85 the nozzle directly into the die.

5. A casting machine having, in combination, a receptacle for the material to be cast, a movable pressure chamber provided with a duct terminating in a nozzle adapted to 95 be submerged below the surface of such material for permitting such material to flow into the pressure chamber through said nozzle, said nozzle providing the only inlet for such material to enter the pressure chamber, 100 means for raising said nozzle above the surface of such material, movable die-supporting means, a die carried by the die-supporting means and adapted to receive directly from the nozzle the material to be cast, and means for supplying and admitting a fluid under pressure into the pressure chamber to act upon the material within the pressure chamber and eject such material from the pressure chamber through said nozzle into 110 the die.

6. A casting machine having, in combination, a receptacle for the material to be cast, a movable pressure chamber provided with a duct terminating in a nozzle adapted to be 115 submerged below the surface of such material for permitting such material to flow into the pressure chamber through said nozzle, said nozzle providing the only inlet for such material to enter the pressure chamber, means for raising said nozzle above the surface of such material, means for locking the pressure chamber in the casting position with its nozzle above the surface of the material in the receptacle, pivoted die-supporting means, a sectional die mounted upon said die-supporting means and movable therewith, such die being adapted to receive 120 125

chamber and eject such material from the pressure chamber through said nozzle into the die, and fluid pressure controlling means for operating the respective pistons of the different fluid pressure means successively, whereby the nozzle is elevated above the surface of the material in the receptacle and locked in that position, and thereafter the die sections are closed and clamped to the nozzle, and whereby after the material has been forced into the die the die sections are unclamped from the nozzle and opened and thereafter the pressure chamber is operated to again submerge the nozzle below the surface of the material in the receptacle.

11. A casting machine having, in combination, a receptacle for the material to be cast, a pressure chamber pivoted for rocking movement and provided with a duct terminating in a nozzle adapted to be submerged below the surface of such material for permitting such material to flow into the pressure chamber through said nozzle, said nozzle providing the only inlet for such material to enter the pressure chamber, fluid pressure means including a piston for imparting rocking movement to the pressure chamber for raising the nozzle above the surface of such material, means for locking the pressure chamber in the casting position with its nozzle above the surface of the material in the receptacle, pivoted die-supporting means, a sectional die mounted upon said die-supporting means and movable therewith, such die being adapted to receive directly from the nozzle the material to be cast, means for clamping the die firmly to the nozzle in the elevated and locked position of the latter, means for supplying and admitting a fluid under pressure into the pressure chamber to act upon the material within the pressure chamber and eject such material from the pressure chamber through said nozzle into the die, a valve device in control of the pressure fluid for the pressure chamber, and means in control of said valve device for preventing the admission of pressure fluid into the pressure chamber until after the die has been clamped to the nozzle.

12. A casting machine having, in combination, a receptacle for the material to be cast, a pressure chamber pivoted for rocking movement and provided with a duct terminating in a nozzle adapted to be submerged below the surface of such material for permitting such material to flow into the pressure chamber through said nozzle, said nozzle providing the only inlet for such material to enter the pressure chamber, fluid pressure means for imparting rocking movement to the pressure chamber for raising the nozzle above the surface of such material, means for locking the pressure chamber in the casting position with its nozzle above the surface of the material in the receptacle, pivoted die-supporting means, a sectional die mounted upon said die-supporting means and movable therewith, such die being adapted to receive directly from the nozzle the material to be cast, means for clamping the die firmly to the nozzle in the elevated and locked position of the latter, fluid pressure means including a piston for moving the die-supporting means on its pivot and whereby the die sections are moved relatively to the nozzle and to each other, means for supplying and admitting a fluid under pressure into the pressure chamber to act upon the material within the pressure chamber and eject such material from the pressure chamber through the nozzle into the die, and fluid pressure controlling means for operating the respective pistons of the different fluid pressure means successively, whereby the nozzle is elevated above the surface of the material in the receptacle and locked in that position, and thereafter the die sections are closed and clamped to the nozzle, and whereby after the material has been forced into the die the die sections are unclamped from the nozzle and opened and thereafter the pressure chamber is operated to again submerge the nozzle below the surface of the material in the receptacle.

cast, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, means for raising said nozzle above the surface of such material, means for locking the pressure chamber in the casting position with its nozzle above the surface of the material in the receptacle, pivoted die-supporting means, a sectional die mounted upon said die-supporting means and movable therewith, such die being adapted to receive directly from the nozzle the material to be cast, means for clamping the die firmly to the nozzle in the elevated and locked position of the latter, means for supplying and admitting a fluid under pressure into the pressure chamber to act upon the material within the pressure chamber and eject such material from the pressure chamber through said nozzle into the die, a valve device in control of the pressure fluid for the pressure chamber, and means in control of said valve device for preventing the admission of pressure fluid into the pressure chamber until after the die has been clamped to the nozzle.

13. A casting machine having, in combination, a receptacle for the material to be cast, a pressure chamber pivoted for rocking movement and provided with a duct terminating in a nozzle adapted to be submerged below the surface of such material for permitting such material to flow into the pressure chamber through said nozzle, said nozzle providing the only inlet for such material to enter the pressure chamber, fluid pressure means for imparting rocking movement to the pressure chamber for raising the nozzle above the surface of such material, means for locking the pressure chamber in the casting position with its nozzle above the surface of the material in the receptacle, pivoted die-supporting means, a sectional die mounted upon said die-supporting means and movable therewith, such die being adapted to receive directly from the nozzle the material to be cast, means for clamping the die firmly to the nozzle in the elevated and locked position of the latter, means for supplying and admitting a fluid under pressure into the pressure chamber to act upon the material within the pressure chamber and eject such material from the pressure chamber through the nozzle into the die, a valve device in control of the pressure fluid for the pressure chamber, and means in control of said valve device for preventing the admission of pressure fluid into the pressure chamber until after the die has been clamped to the nozzle.

14. A casting machine having, in combination, a receptacle for the material to be cast, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, fluid pressure means including a piston for raising said nozzle above the surface of such material, means for locking the pressure chamber in the casting position with its nozzle above the surface of the material in the receptacle, pivoted die-supporting means, a sectional die mounted upon said die-supporting means and movable therewith, such die being adapted to receive directly from the nozzle the material to be cast, means for clamping the die firmly to the nozzle in the elevated and locked position of the latter, fluid pressure means including a piston for moving the die-supporting means on its pivot and whereby the die sections are moved relatively to the nozzle and to each other, means for supplying and admitting a fluid under pressure into the pressure chamber to act upon the material within the pressure chamber and eject such material from the pressure chamber through said nozzle into the die, fluid pressure controlling means for operating the respective pistons of the different fluid pressure means successively, whereby the nozzle is elevated above the surface of the material in the receptacle and locked in that position and thereafter the die sections are closed and clamped to the nozzle, and whereby after the material has been forced into the die the die sections are unclamped from the nozzle and opened and thereafter the pressure chamber is operated to again submerge the nozzle below the surface of the material in the receptacle, a valve device in control of the pressure fluid for the pressure chamber, and means in control of said valve device for preventing the admission of pressure fluid into the pressure chamber until after the die has been clamped to the nozzle.
15. A casting machine having, in combination, a receptacle for the material to be cast, a pressure chamber pivoted for rocking movement and provided with a duct terminating in a nozzle adapted to be submerged below the surface of such material for permitting such material to flow into the pressure chamber through said nozzle, said nozzle providing the only inlet for such material to enter the pressure chamber, fluid pressure means including a piston for imparting rocking movement to the pressure chamber for raising the nozzle above the surface of such material, means for locking the pressure chamber in the casting position with its nozzle above the surface of the material in the receptacle, movable die-supporting means, a die carried by the die-supporting means to move therewith and adapted to receive directly from the nozzle the material to be cast, means for clamping the die firmly to the nozzle in the elevated and locked position of the latter, and means for supplying and admitting a fluid under pressure into the pressure chamber to act upon the material within the pressure chamber and eject such material from the pressure chamber through said nozzle into the die.
16. A casting machine having, in combination, a receptacle for the material to be cast, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, means for raising said nozzle above the surface of such material, means for locking the pressure chamber in casting position with its nozzle above the surface of the material in the receptacle, pivoted die-supporting means, a sectional die mounted upon said die-supporting means and movable therewith, such die being adapted to receive directly from the nozzle the material to be cast, means for clamping the die firmly to the nozzle in the elevated and locked position of the latter, fluid pressure means including a piston for moving the die-supporting means on its pivot and whereby the die sections are moved relatively to the nozzle and to each other, means for supplying and admitting a fluid under pressure into the pressure chamber to act upon the material within the pressure chamber and eject such material from the pressure chamber through the nozzle into the die, fluid pressure controlling means for operating the respective pistons of the different fluid pressure means successively, whereby the nozzle is elevated above the surface of the material in the receptacle and locked in that position and thereafter the die sections are closed and clamped to the nozzle, and whereby after the material has been forced into the die the die sections are unclamped from the nozzle and opened and thereafter the pressure chamber is operated to again submerge the nozzle below the surface of the material in the receptacle, a valve device in control of the pressure fluid for the pressure chamber, and means in control of said valve device for preventing the admission of pressure fluid into the pressure chamber until after the die has been clamped to the nozzle.
17. A casting machine having, in combination, a receptacle for the material to be

cast, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, fluid pressure means for raising said nozzle above the surface of such material, means for locking the pressure chamber in the casting position with its nozzle above the surface of the material in the receptacle, movable die-supporting means, a die carried by the die-supporting means to move therewith and adapted to receive directly from the nozzle the material to be cast, means for clamping the die firmly to the nozzle in the elevated and locked position of the latter, fluid pressure means for moving the die-supporting means together with the die carried thereby, and means for supplying and admitting a fluid under pressure into the pressure chamber to act upon the material within the pressure chamber and eject such material from the pressure chamber through said nozzle into the die.

18. A casting machine having, in combination, a receptacle for the material to be cast, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, fluid pressure means including a piston for raising said nozzle above the surface of such material, means for locking the pressure chamber in the casting position with its nozzle above the surface of the material in the receptacle, movable die-supporting means, a die carried by the die-supporting means to move therewith and adapted to receive directly from the nozzle the material to be cast, means for clamping the die firmly to the nozzle in the elevated and locked position of the latter, fluid pressure means including a piston for moving the die-supporting means together with the die carried thereby, means for supplying and admitting a fluid under pressure into the pressure chamber to act upon the material within the pressure chamber and eject such material from the pressure chamber through said nozzle into the die, and fluid pressure controlling means for operating the respective pistons of the different fluid pressure means successively, whereby the nozzle is elevated above the surface of the material in the receptacle and locked in that position and thereafter the die is clamped to the nozzle, and whereby after the material has been forced into the die the die is unclamped from the nozzle and

thereafter the pressure chamber is operated 65 to again submerge the nozzle below the surface of the material in the receptacle.

19. A casting machine having, in combination, a receptacle for the material to be cast, a movable pressure chamber provided 70 with a duct terminating in a nozzle adapted to be submerged below the surface of such material for permitting such material to flow into the pressure chamber through said nozzle, said nozzle providing the only inlet 75 for such material to enter the pressure chamber, means for raising said nozzle above the surface of such material, means for locking the pressure chamber in casting position with its nozzle above the surface 80 of the material in the receptacle, movable die-supporting means, a die carried by the die-supporting means to move therewith and adapted to receive directly from the nozzle the material to be cast, means for 85 clamping the die firmly to the nozzle in the elevated and locked position of the latter, means for supplying and admitting a fluid under pressure to the pressure chamber to act upon the material within the pressure 90 chamber and eject such material from the pressure chamber through said nozzle into the die, a valve device in control of the pressure fluid for the pressure chamber, and means in control of said valve device for 95 preventing the admission of pressure fluid into the pressure chamber until after the die has been clamped to the nozzle.

20. A casting machine having, in combination, a receptacle for the material to be cast, a movable pressure chamber provided 100 with a duct terminating in a nozzle adapted to be submerged below the surface of such material for permitting such material to flow into the pressure chamber through said nozzle, said nozzle providing the only inlet 105 for such material to enter the pressure chamber, fluid pressure means for raising said nozzle above the surface of such material, means for locking the pressure chamber in the casting position with its nozzle above the surface of the material in the receptacle, movable die-supporting means, a die carried by the die-supporting means to move therewith and adapted to receive directly from the nozzle the material to be cast, means for 110 clamping the die firmly to the nozzle in the elevated and locked position of the latter, fluid pressure means for moving the die-supporting means together with the die carried thereby, means for supplying and admitting a fluid under pressure into the pressure chamber to act upon the material within the pressure chamber and eject such material from the pressure chamber through said nozzle into the die, a valve device in control of the pressure fluid for 115 moving the die-supporting means together with the die carried thereby, means for supplying and admitting a fluid under pressure into the pressure chamber to act upon the material within the pressure chamber and eject such material from the pressure chamber through said nozzle into the die, a valve device in control of the pressure fluid for 120 the pressure chamber, and means in control 125

of said valve device for preventing the admission of pressure fluid into the pressure chamber until after the die has been clamped to the nozzle.

- 5 21. A casting machine having, in combination, a receptacle for the material to be cast, a movable pressure chamber provided with a duct terminating in a nozzle adapted to be submerged below the surface of such material for permitting such material to flow into the pressure chamber through said nozzle, said nozzle providing the only inlet for such material to enter the pressure chamber, fluid pressure means including a piston for raising said nozzle above the surface of such material, means for locking the pressure chamber in the casting position with its nozzle above the surface of the material in the receptacle, movable die-supporting means, a die carried by the die-supporting means to move therewith and adapted to receive directly from the nozzle the material to be cast, means for clamping the die firmly to the nozzle in the elevated and locked position of the latter, fluid pressure means including a piston for moving the die-supporting means together with the die carried thereby, means for supplying and admitting a fluid under pressure into the pressure chamber to act upon the material within the pressure chamber and eject such material from the pressure chamber through said nozzle into the die, fluid pressure controlling means for operating the respective pistons of the different fluid pressure means successively, whereby the nozzle is elevated above the surface of the material in the receptacle and locked in that position and thereafter the die is clamped to the nozzle, and whereby after the material has been forced into the die the die is unclamped from the nozzle and thereafter the pressure chamber is operated to again submerge the nozzle below the surface of the material in the receptacle, a valve device in control of the pressure fluid for the pressure chamber, and means in control of said valve device for preventing the admission of pressure fluid into the pressure chamber until after the die has been clamped to the nozzle.
22. A die casting machine comprising a receptacle for the material to be cast, a movable ladle provided with a duct terminating in a nozzle, means for admitting the material to be cast into the ladle, a movable die adapted to receive directly from the nozzle the material to be cast, and means for forcing the material to be cast from the ladle through the nozzle directly into the die.
23. A die casting machine comprising a receptacle for the material to be cast, a movable ladle provided with a nozzle mounted thereon, means for admitting the material

to be cast into the ladle, a movable die, means for moving the die and nozzle relatively to each other, means for locking the die to the nozzle just above the surface of the material to be cast, and means for forcing the material to be cast from the ladle through the nozzle directly into the die.

24. A casting machine having in combination a melting pot, a movable pressure chamber terminating in a nozzle adapted to be submerged below the surface of the molten metal, means for moving the pressure chamber so that the nozzle is just above the surface of the molten metal, a movable die, means for locking the die to the nozzle, and means for forcing the molten metal from the pressure chamber through the nozzle directly into the die.

25. A casting machine having in combination a melting pot, a movable ladle terminating in a nozzle adapted to be submerged below the surface of the molten metal, means for moving and locking the ladle so that the nozzle is just above the surface of the molten metal, a movable die, means for locking the die to the nozzle, and means for forcing the molten metal from the ladle through the nozzle directly into the die.

26. A die casting machine comprising a melting pot, a movable ladle terminating in a nozzle adapted to be submerged below the surface of the molten metal, means for moving the ladle so that the nozzle is held above the surface of the molten metal whereby the ladle and the nozzle partake of the heat of the molten metal, a sectional die, means for moving the die sections relatively to each other and to the nozzle, means for locking the die sections to the nozzle, and means for forcing the molten metal from the ladle through the nozzle directly into the die.

27. A casting machine having in combination a receptacle for the material to be cast, a movable pressure chamber terminating in a nozzle, means for admitting the molten metal into the pressure chamber, means for raising said nozzle above the surface of the molten metal, a movable die, and fluid pressure means to discharge the molten metal directly into the die.

28. A casting machine having in combination a melting pot, a movable die, a movable pressure chamber terminating in a nozzle adapted to be submerged below the surface of the molten metal, means for raising and locking said nozzle above the surface of the molten metal, and means for supplying and admitting a fluid under pressure into the pressure chamber to force the molten metal from the pressure chamber through the nozzle directly into the die.

29. A die casting machine having in combination a melting pot, a pressure chamber terminating in a nozzle, mounted to rotate

in said melting pot, means for rotating the pressure chamber so that the nozzle is submerged below the surface of the molten metal at one limit of movement of said pressure chamber and adapted to lock with the nozzle just above the surface of the molten metal at the other limit of said movement,

and means for supplying air under pressure to the pressure chamber for forcing the molten metal from the pressure chamber ¹⁰ through the nozzle directly into the die.

In testimony whereof I have affixed my signature.

GEORGE WALDEMAR BUNGAY.
